(57) **CLAIM**

The ornamental design for a roller die press, as shown and described.

DESCRIPTION

FIG. 1 is a perspective view of the roller die press;
 FIG. 2 is a perspective view of the roller die press;
 FIG. 3 is a front side view of the roller die press;
 FIG. 4 is a back side view of the roller die press;
 FIG. 5 is a left side view of the roller die press;
 FIG. 6 is a right side view of the roller die press;
 FIG. 7 is a top side view of the roller die press; and,
 FIG. 8 is a bottom side view of the roller die press.

1 Claim, 4 Drawing Sheets
